UNITED STATES PATENT OFFICE.

ALBERT H. BRIGHAM, OF WHITMAN, MASSACHUSETTS.

APPARATUS FOR HEADING NAILS OR TACKS.

1,105,614.

Specification of Letters Patent.

Patented Aug. 4, 1914.

Application filed June 6, 1913. Serial No. 772,093.

To all whom it may concern:

Be it known that I, ALBERT H. BRIGHAM, a citizen of the United States, residing at Whitman, county of Plymouth, State of Massachusetts, have invented an Improvement in Apparatus for Heading Nails or Tacks, of which the following description, in connection with the accompanying drawing, is a specification, like characters on the drawing representing like parts.

My invention relates to apparatus for heading nails tacks or the like and is an improvement over the devices shown in my prior Patents Nos. 589,495, 658,203 and 5 722,669. Said devices include a die carrier, a heading pin secured in the die carrier and a die which is guided by the die carrier and into which the heading pin is slideable. In these devices considerable difficulty has been 20 experienced because the die is not guided with sufficient accuracy in its movement and frequent breakage of the heading pin results. One of the objects of the present invention is to prevent this breakage and to 25 provide a more simple device. This is accomplished by providing a long bearing in the die carrier for the die, the bearing being preferably considerably longer than the diameter of the die and I provide a novel device 30 for holding the heading pin and thrust screw securely in the die carrier, and in my preferred forms obviating the need of a check screw.

Other objects will appear from the following specification and the novel features 35 will be pointed out in the claims.

In the drawing in which my invention is illustrated, Figure 1 is a sectional view showing the heading tool in position in the 40 heading lever; Fig. 2 is a view of a portion of the heading tool drawn to an enlarged scale; Fig. 3 is a section on the line 3—3 of Fig. 2; Fig. 4 is a longitudinal section showing a modified construction; and 45 Fig. 5 is a similar section showing another modification.

Referring to the drawings in detail 1 indicates the heading lever in which the heading tool 2 is adjustably mounted. This tool 50 is clamped in position by a set-screw 3 between which and the tool a block 4 is inserted. A thrust-screw 5 is provided for the

purpose of adjusting the tool longitudinally and holding it in adjusted position. 6 and 7 represent gripping dies between which the 55 blank is held while the head is being formed. These dies are of usual construction having suitable depressions or seats to shape the under side of the head. The heading tool comprises a longitudinally bored die carrier 8, a heading pin 9 secured in the bore of the die carrier by the holder 10 and a die 11 slidably connected to the die carrier and in which the heading pin slides.

In accordance with my present invention 65 the die carrier is cylindrical and has a long sliding bearing as at 12 in the forward portion of the bore of the die carrier fitting as closely as is consistent with free longitudinal movement.

I shall first describe the structure shown 70 in Figs. 1, 2 and 3. The carrier is longitudinally slotted as shown at 13 preferably from its rear end to a point 14 adjacent the portion in which the die is mounted. The 75 holder 10 is split longitudinally as shown at 15 and is preferably so positioned in the carrier that the position of its slot will coincide with the position of the slot 13 of the carrier. The heading pin is slideable in the 80 bore of the die and extends through the split holder by which it is securely clamped in position in the carrier. The set screw 3 when tightened clamps the tool in position in the heading lever and also clamps the adjusting 85 screw 17 at the same time thus obviating the necessity of a check screw. The bore of the die carrier is threaded at 16 to receive the thrust screw 17 which takes the thrust of the heading pin. This form of 90 holder and die carrier insures accurate centering of the heading pin in the holder and prevents the breakage due to inaccurate alinement of the die and heading pin. As a simple method of limiting the movement 95 of the die in the carrier, I provide a screw 18 the end of which projects into a recess 19 of the die. The end of the screw is preferably made eccentric as shown at 20 making possible a limited adjustment. The lock-nut 21 is provided to secure the screw in 100 adjusted position. A spring 22 is mounted in the die carrier behind the die to hold it in forward position.

Fig. 4 shows a modified structure in which the die carrier is made in two parts the body portion 23 being threaded at its forward end to receive the bushing 24. The die 25 has a long bearing in the bore of the bushing 24 and is provided with an annular radial flange 26 which engages the inner end of the bushing and limits the outward movement of the die. In other respects this 10 modification is similar to that shown in Figs. 1, 2 and 3.

In the modification shown in Fig. 5 the die carrier 27 is longitudinally bored as in the other modifications but is not split. The 15 holder is omitted. Instead a set screw 28 is provided which bears against the heading pin 29 and holds it in adjusted position. The die 30 is similar to that shown in Figs. 1, 2 and 3 and its motion is similarly limited 20 by an adjustable screw and lock-nut. A spring 31 bears against the rear end of the die and normally holds it in forward position. A collar 32 may be provided to reinforce the heading pin if desired. A thrust screw 33 is provided for adjusting the heading pin longitudinally and taking the thrust thereof, a check screw 34 being provided to lock the said thrust screw in adjusted position.

30 In all the modifications shown, the die extends some little distance beyond the end of the die carrier so that it may be ground off to provide a new portion as the bore of the die wears.

35 I have illustrated and described the heading pin as rigidly secured in the holder. It is only essential, however, that the heading pin should be so arranged that it can not move too far forward or be accidentally removed from the tool.

40 The operation of the device will be clear from the previous description.

Having described my invention, what I 45 claim as new and desire to secure by Letters Patent is:—

1. In a device of the class described, a die carrier having a longitudinal bore, and split longitudinally for a portion of its length, a cylindrical die longitudinally bored and having a long bearing in the bore of the carrier, a heading pin slidable in the bore of the die and extending longitudinally in the bore of the carrier, an adjusting thrust screw threaded into the bore of the carrier and abutting 50 against the heading pin, a longitudinally split holder embracing the heading pin and fitting in the bore of the die carrier and means to clamp the die carrier, split holder, heading pin and thrust screw together in operative position.

2. In a device of the class described, a die carrier having a longitudinal bore and split longitudinally for a portion of its length, a cylindrical die longitudinally bored and having 65 a long bearing in the bore of the carrier,

a heading pin slidable in the bore of the die and extending longitudinally in the bore of the carrier, a longitudinally split holder embracing the heading pin and fitting in the bore of the die carrier and means to clamp the carrier, holder and heading pin together. 70

3. In a device of the kind described, a die carrier comprising a body portion and a bushing secured in the end of the body portion, a longitudinally bored die slidable in the bushing and having a radial flange adapted to engage the inner end of the bushing to limit the outward movement of the die and a heading pin secured in the carrier and slidable in the bore of the die. 75

4. In a device of the kind described, a die carrier comprising a body portion having a longitudinal bore and split for a portion of its length and a bushing removably secured in the end of the body portion, a longitudinally bored die having a long sliding bearing in the bushing and provided with a radial flange adapted to engage the inner end of the bushing and limit the relative movement, a heading pin slidable in the bore of the die and extending longitudinally in the bore of the carrier, a split holder embracing the heading pin and fitting in the split portion of the carrier and means to clamp the carrier, holder and heading pin together. 80

5. In a device of the class described, a die carrier comprising a body portion having a longitudinal bore and split for a portion of its length, a bushing removably secured in the end of the body portion of the die carrier, a longitudinally bored die having a long sliding bearing in the bushing and provided with a radial flange adapted to engage the inner end of the bushing and limit the relative movement, a heading pin slidable in the bore of the carrier, a thrust adjusting screw threaded in the bore of the carrier and abutting the heading pin, a split holder embracing the heading pin and fitting in the split portion of the carrier, and clamping means to clamp the die carrier at its split portion and thus lock the split holder, heading pin, and thrust screw in operative position. 90

6. A heading tool comprising a die carrier having a cylindrical bore in its forward end, a centrally bored cylindrical die bearing in the bore of the die carrier for the greater portion of its length whereby accurate alinement of the die carrier and die during the movement of the latter is assured, means to limit the movement of the die in the die carrier, and a heading pin secured in the die carrier and slidable in the bore of the die. 100

7. A heading tool comprising a die carrier having a cylindrical bore in its forward end, a centrally bored die slidable in the bore of the die carrier and bearing therein for a 110

distance greater than the diameter of the die whereby accurate alinement of the die in the die carrier during the movement of the die is assured, means to limit the movement of the die in the die carrier, and a heading pin slidable in the bore of the die.

5 In testimony whereof, I have signed my

name to this specification, in the presence of two subscribing witnesses.

ALBERT H. BRIGHAM.

Copies of this patent may be obtained for five cents each, by addressing the "Commissioner of Patents, Washington, D. C."

Correction in Letters Patent No. 1,105,614,

It is hereby certified that in Letters Patent No. 1,105,614, granted August 4, 1914, upon the application of Albert H. Brigham, of Whitman, Massachusetts, for an improvement in "Apparatus for Heading Nails or Tacks," an error appears in the printed specification requiring correction as follows: Page 2, line 104, strike out the words and comma "carrier, a thrust adjusting" and insert the words *die and extending longitudinally*; and that the said Letters Patent should be read with this correction therein that the same may conform to the record of the case in the Patent Office.

Signed and sealed this 1st day of September, A. D., 1914.

[SEAL.]

R. F. WHITEHEAD,

Acting Commissioner of Patents.
